UNITED STATES PATENT OFFICE.

ALBERT MUDRA, OF LINCOLN, NEBRASKA.

DESIGN FOR A HIP-STRAP DROP FOR HARNESS.

SPECIFICATION forming part of Design No. 35,930, dated June 3, 1902.

Application filed March 24, 1902. Serial No. 99,817. Term of patent 7 years.

To all whom it may concern:

Be it known that I, ALBERT MUDRA, a citizen of the United States, residing at Lincoln, in the county of Lancaster and State of Nebraska, have invented and produced a new and original Design for a Hip-Strap Drop for Harness, of which the following is a specification, reference being had to the accompanying drawings, forming part thereof.

10 My invention relates to a new and original design for a hip-strap drop for harness, and has for its object to provide a design which is very artistic and ornamental in appearance and also useful.

15 The leading and material features of the design consist in a hip-strap drop with a substantially rectangular upper portion, a substantially circular lower portion, V-shaped notches on the sides between said upper and lower portions, the body of the rectangular portion provided with an elongated slot, the lower portion of which curves downward to a point at approximately the center thereof, and the body of the lower portion below this 25 slot provided with an inverted-heart-shaped opening with inwardly-projecting lobes.

In the drawings which illustrate my design, Figure 1 is a front view, and Fig. 2 a side edge view.

30 Referring to the drawings, the design in its

entirety comprises a hip-strap drop with a substantially rectangular upper portion 1, a substantially circular lower portion 2, the side edges of said upper portion extending outwardly and forming rounded projections 3 35 and then inwardly and forming V-shaped notches 4 at their point of juncture 5 with the circular lower portion 2. The body of the upper portion is provided with an elongated slot 6, an elongated slot 7 with rounded ends 40 8, and the lower edge of which curves downwardly about midway of its ends and terminates in a point 9. The body of lower circular portion is provided with an inverted-heart-shaped opening 10, having on its opposite side edges inwardly-projecting semicircular lobes 11, a pear-shaped opening 12, and an elongated curved slot 13.

Having thus described my design, what I claim is—

50 The design for a hip-strap drop as herein shown and described.

In testimony whereof I have hereunto affixed my signature in the presence of the two subscribing witnesses.

ALBERT MUDRA.
